UNITED STATES PATENT OFFICE.

JUNIUS E. BUSBY, OF HAZARD, KENTUCKY.

TRACK AND CURVE GAUGE.

Application filed February 27, 1922. Serial No. 539,622.

To all whom it may concern:

Be it known that I, JUNIUS E. BUSBY, a citizen of the United States, residing at Hazard, in the county of Perry and State 5 of Kentucky, have invented certain new and useful Improvements in Track and Curve Gauges, of which the following is a specification, reference being had to the accompanying drawings.

10 It is the purpose of the present invention to provide a track gauge for properly spacing the rails on straight tracks, and for locating center stakes for properly lining up and spacing curved rails on a curve, as well 15 as leveling the rails, and also for elevating the outer rail of a curve, without the aid of a civil engineer.

Another purpose is the provision of an improved gauge of this character, wherein simple, efficient and practical features of construction are involved.

It is to be understood that the particulars herein given are in no way limitative and that while still keeping within the scope of 25 the invention, any desired modifications of detail and desired proportions may be made in the apparatus according to circumstances.

The invention comprises further features and combination of parts, as will be herein- 30 after set forth, shown in the drawings and claimed.

In the drawings:—

Figure 1 is a view in perspective showing the improved gauge constructed in accord- 35 ance with the invention;

Figure 2 is a plan view of the same;

Figure 3 is a view in side elevation showing the gauge as applied to the opposite rails of the track;

40 Figure 4 is a sectional view on line 4—4 of Figure 1;

Figure 5 is an enlarged detail view of the detachable gauge rule 33, with it disposed on its edge, for measuring the easement of the 45 rails;

Figure 6 is a detail view in elevation of one end of the track gauge, showing it clamped to a rail in section;

50 Figure 7 is an enlarged detail view of the detachable gauge extension, for measuring the elevation of the outer rail;

Figure 8 is an enlarged detail plan view of the rule 41 and the blocks 38 and 39;

Figure 9 is a diagram of a track showing the curve, which in the present instance has 55 been found to be a four degree curve;

Figure 10 is a diagram of a track showing a four degree curve therein, showing the method of finding the location of the easement and the tangent junction where the 60 straight portion of the track merges into the curve;

Figure 11 is a view wherein the rule 33 is used in connection with and upon the track gauge, for measuring and locating the proper 65 position of the outer rail, according to the easement to be used; and

Figure 12 is a view showing the use of the rule 33 detached from the track gauge, in order to line up the stakes between the rails, 70 so that the inside rail on the curve may be lined relatively to the stakes.

Referring to the drawings, 1 designates the usual form of track gauge, which comprises the tubular body 2 terminating in a rectangular fork 3 at one end, the arms of which rest upon the ball of the rail, whereas the spurs 4 engage the side of the ball of the rail. A holding plate or clamp 5 also rests upon the ball of the rail, and has at one end 75 an enlargement 6, which rests upon the transverse part of the fork at one end of the body of the gauge. The enlargement 6 has downwardly extending lugs 7, which straddle the body of the gauge, where it 80 merges into the transverse portion of the forks. The other end of the plate or clamp 5 terminates in a downwardly extending ear 8 provided with a thumb screw 9, which bears against one side of the ball of the rail, 85 for the purpose of drawing the spurs tight against the rail, and thereby holding the gauge in position.

Mounted in any suitable manner upon the body of the gauge adjacent the opposite end 95 of the body is a conventional form of spirit level 10, which is held on the body by the support 11 in any suitable manner. The opposite longitudinal edges of a cover plate 12, which engages over the spirit level and is secured to the support, is provided with guides 13 to receive a slide 14, which covers 100

the spirit level. When it is desired to read the spirit level, the slide may be moved back, so that the level is visible.

One end of the body of the gauge has a 5 socket 15, to receive a reduced portion 16 of the gauge extension 17. The reduced portion of the gauge extension has graduations, for measuring the adjustment of the gauge extension, there being a thumb screw 10 threaded through the wall of the socket and engaging the reduced portion of the gauge extension, for holding it in different positions. A rule 18 provided with graduations 19 for measuring the elevation of a 15 rail is mounted in a transverse slot 20 at the end of the gauge extension, there being a thumb screw 21 threaded through the wall of the slot to bear upon the rule, thereby holding it in different adjusted positions.

20 The gauge extension has a downwardly protruding abutment lug 22, which engages the outer edge of the ball of the outer rail, when the gauge is used for ascertaining whether or not the rails are properly spaced.

25 A centering block 23 is mounted on the body of the gauge and comprises two sections bolted together as at 24. A thumb screw 25 engages through one of the sections and bears against the tubular gauge 30 body, for holding the centering head or block in position relatively upon the body of the gauge. In order to hold the centering block in a horizontal position a guide rod 26 is provided. This rod has lateral 35 ends 27, which are reduced at 28, and are disposed transversely of the tubular gauge body. The terminals of the reduced portions 28 are threaded for the reception of nuts 29, to hold the ends of the guide rod 40 rigid, and thereby holding the rod rigid in a position laterally of the tubular gauge body. The guide rod passes through a bushing 30, which is mounted between the two sections of the centering block or head.

45 The adjacent faces of the two sections of the centering block or head have recesses, which, owing to the sections being clamped together, cause to be formed a slot 31, for the reception of the enlarged end 32 of the 50 gauge rule 33. The enlarged end 32 of the gauge rule has an opening 34, which receives a perpendicularly disposed centering pin or rod 35, which passes through the centering block or head. A thumb screw 36 is 55 threaded upon the upper section of the centering head or block and bears upon the centering pin or rod, thereby holding it in different positions, and at the same time anchoring the gauge rule in place.

60 The gauge rule is provided with graduations from one to thirty-three in inches and fractions thereof, for instance half and quarter inches. A slide comprising blocks 65 38 and 39 is mounted on the gauge rule, and projecting from the blocks are pins 40,

which enter openings of what may be termed an easement measuring rule 41, which is also provided with graduations. An abutment facing plate 42 is secured upon the block 39 and is adapted to engage the 70 side of the ball of the rail, when the gauge rule is detached from the gauge body, and employed for measuring whether or not the rails on a curve are properly spaced. Suitable thumb screws 43 engage through the blocks 38 and 39, for holding the slide in position. The block 38 has a sight opening 44, there being an indicator 45 engaged through the wall of the block 38, so that the 75 end of the indicator may be seen through 80 the opening 44.

A centering or fulcrum plate 46, which is tapered or V-shaped to a sharpened point is used in connection with the gauge rule, when detached, when measuring whether or 85 not the opposite rails on a curve are properly aligned or spaced, throughout the curvature of the track. This centering or fulcrum plate has a flange 47, which engages one edge of the gauge rule, there being lugs 90 48 which engage along one of the edges of the gauge rule, to hold the fulcrum or centering plate rigid with relation to the gauge rule. A bolt 49 passes through the fulcrum or centering plate and through the gauge 95 rule, and is provided with a nut 50, for securing the plate in position.

Before starting to stake the curve in a track it is necessary to find the degree to curve. This can be accomplished by first 100 locating the tangent junction or point, where the straight portion of the track merges into the curve. For instance an operator may stand on the straight portion of the side rail, substantially at 50, sighting along the rail, using a transit, or using a cord lying on the straight portion of the rail, in connection with the plumb, and immediately where the inside rail starts to curve off from the straight portion of the rail, the point of tangent may be located by making a cross mark at 51. A similar cross mark may be made directly opposite the cross mark 51, on the outer rail, where the tangent junction or point of the outer rail may be located. A 105 tape is then used to measure from the tangent point on the outer rail back upon the straight portion of the outer rail for 31 feet. A 50 foot tape line is then used, commencing to 110 measure from the extra measurement point 52 on the outer rail to the tangent junction or point at 53, and then from this point along the rail every 31 feet, and at every 31 feet a cross mark 54, such as shown in Figure 9 is made on the base of the rail, until the workman reaches the tangent junction or point at 55, and the point of extra measurement at 56 on the other side of the curve. After measuring around the entire curve, 115 making the cross marks, a 62 foot track cord 120

125

130

is then employed. For instance this 62 foot track cord is provided with a knot in its center, so that the cord on each side of the knot will extend 31 feet. This cord is 5 stretched tight against the inside edge of the outer rail, one workman holding the cord to the rail at 52, another workman holding the cord against the rail at 54, in which case the knot in the 62 foot track cord will 10 locate itself opposite the point 53. Each time this 62 foot track cord (not shown), but diagrammed as at 57 in Figure 9 is held against the inside of the outer rail consecutively 31 feet apart, a measurement is taken 15 from the center of the cord where the knot is located to the rail. A notation of this amount is made. After the curve of the outer rail has measured in this manner, these amounts are totaled, and the sum there- 20 of is then divided by the number of times the measurements are made.

For instance the dotted line 57 represents the 62 foot curve track cord, and the various amounts, beginning at the left hand end of Figure 9 represents the distances between the cord and the rail, such as 2", 3 $\frac{3}{16}$ ", 4 $\frac{3}{16}$ ", 3 $\frac{4}{16}$ " and so on about the entire curve of the outer rail. It will be noted that the outer rail in Figure 9 is measured in this manner twenty-one times, and the sum total of the amounts of the measurements in Figure 9 equals 84" divided by 21, the number of times the measurements are taken, equals 4, therefore the illustration in Figure 9 is that of a four degree curve. In adding the amounts adjacent the outer rail in Figure 9, the whole numbers are first added, and then the fractions. The sum total of the whole numbers gives 80", while the sum total of the fractions in sixteenths gives $\frac{64}{16}$, divided by 16 gives 4", which added to 80 makes a total of 84".

Example.

50 Having found the degree of curve, and located the tangent junction and the length of the easement, it is then necessary to locate the stakes between the inner and outer rails. These stakes are placed directly opposite the cross marks 54, but in order to do this, the track gauge, with the rule 33 attached is used in connection with the 62 foot curve track cord, which is placed as in Figure 11. The cord is stretched tight 60 against the inside edge of the outer rail of the curve, the gauge is placed across the track with the small end of the gauge facing the outside rail, with the graduated rule 33 attached to the sliding centering block. 65 The easement rule 41 also remains attached.

The gauge in this condition is placed at the tangent junction, the rule 33 having been arranged, with the 62 foot curve track cord in position. The easement rule 41 is arranged so that its first notch No. 1 may be engaged by the track cord, and wherever the centering block occurs, a stake is driven into the ground under the block between the two rails, and is then punched with the centering pin. The gauge is then removed relatively to the track at the third cross mark, and again disposed so that the curve track cord may engage the second notch of the rule 41, and afterward a stake is driven in position under the centering block. This is done consecutively for the entire length of the easement for 186', up to the seventh notch of the rule 41. Each time the gauge is so moved, a stake is driven, and since all rails are laid on a standard basis of $56 \frac{1}{2}$ " apart, the track gauge is then used beyond the easement, to locate stakes exactly $28 \frac{1}{4}$ " from the inside of the outer rail, for a distance from one full curve point 58 to the other full curve point 59. The track gauge with the rule 33 and the easement rule 41 applied in position as previously stated is then placed at 7 at the end of the easement on the opposite side of the curve, and the gauge moved every 31 feet, the 62 foot track cord being held against the inside of the outer rail, so that the cord will engage the notches of the rule 41, beginning with 7 and continuing in a decreasing order to the first notch. It is obvious that when the stakes are placed in this manner they are not set exactly in the center, but after the rails have been lined properly on the opposite sides of the stakes, they will assume central positions.

After the stakes have been driven into place in this manner, the rule 33 together with its easement rule 41 is detached from the track gauge, and the metal centering or fulcrum plate 46 is attached to the end of the rule 33, so that the rule 33 may stand upon its edge when in position. The attachment of the centering or fulcrum plate 46 is accomplished by means of the bolt 49. The block 39 which supports the easement rule 41 is placed so that the facing plate thereon will register at 28 1/4. This produces a lining stick or rule. The rule 33 is then turned edgewise placing block 39 so that its facing plate 43 may engage against the inside edge of the outer rail opposite one of the sticks, then the track can be moved so that the end of the fulcrum or centering plate 46 may engage on a tack driven into the center of the stake, then it is possible to know that the tack is exactly in the center between the two rails. The easement rule 41 is not used during this procedure, but it is not necessary to detach it from the rule 33

because it is not in the way. It is obvious that the gauge of the track being 4' 8 1/2" wide or 56 1/2" wide, half of this amount is 28 1/4", therefore placing outside edge 5 of block 39 at 28 1/4 and using the fulcrum or centering plate 46 it will measure exactly 28 1/4" from the center of the bolt 49 to the facing plate 42 of block 39.

The easement of the outer rail is that portion 10 of the rail which will impart a spiral turn to the train or rolling stock, as the curve of track is taken.

In order to locate the point of tangent and the point of full curve, thereby locating the 15 length of the easement a workman uses a transit or cord, sighting from the straight portion 50 of the track to a plumb on the outer rail, as indicated by the dotted line 59 in Figure 10. In locating the easement, a 20 basis of 186' is used for the length of the easement, as shown in the diagram in Figure 10, for a four degree curve. This 186' may be divided by 31 feet, since it is the aim to drive a stake between the rails every 31 feet, 25 around the curve. Therefore dividing 186 by 31, an easement of six divisions measuring 31 feet apart is obtained, which constitutes six string lengths. As the finding of the easement is worked on a basis of a 30 four degree curve, as shown in Figure 9, which is equal to 4" between a 62 foot track cord and the rail, on the full curve portion of the rail, it is the purpose to multiply the 4" by 16, changing them into sixteenths, the 35 result of which is 64/16. This is divided by 6, since it is the aim to use six measurements for an easement on the curve, therefore 64 divided by 6 equals

$$\begin{array}{r} 10 \frac{2}{3} \\ \hline 16 \end{array}$$

therefore the easement increases

$$\begin{array}{r} 10 \frac{2}{3} \\ \hline 16 \end{array}$$

every 31 feet until it amounts to 4", as shown 45 in the diagram in Figure 10. The easement rule 41 is exactly 4" from notch 1 to notch 7, divided in six equal parts, these notches 50 being

$$\begin{array}{r} 13 \frac{2}{3} \\ \hline 16 \end{array}$$

apart, as the present device is worked on a 55 basis of a four degree curve. However all curves are worked on the same principles, except the easement is figured according to the degree of curve and the number of measurements 31 feet apart to be used on each 60 easement. In order to correct the track, that is the outer rail of the track, and in order to provide the proper easement, the rule 33 is detached from the gauge, the blocks 38 and 39 are adjusted so that when 65 the block 39 is placed against the outer rail,

the outer rail at the point of tangent is positioned right at the notch 1, thereby making an increase of

$$\begin{array}{r} 10 \frac{2}{3} \\ \hline 16 \end{array}$$

70

of an inch. The rule 33 is then moved to the next point of 31 feet from the point of tangent in a direction along the easement, and the blocks 38 and 39 adjusted so that the outer rail may register with the second notch 2 on the easement rule 41. These different adjustments are made during the time of making the consecutive measurements until the end of the easement is reached at a point indicated at 58, and at the time of making these different adjustments and measurements, a tack is driven into the stake immediately under the point of the centering or fulcrum plate 46. The same operation is performed to construct the opposite easement, and after the tacks are thus disposed, the inner rail of the curve of the track is adjusted or rearranged so as to be positioned exactly 28 1/4" from each stake, 31 feet apart.

Since the easement consists of six measurements including the curve track cord and the rail of

$$\begin{array}{r} 10 \frac{2}{3} \\ \hline 16 \end{array}$$

63

of an inch every 31 feet, thereby providing the six string lengths of 31 feet, the sum of these amounts is 64, as the example below 100 will show.

Example.

$$\begin{array}{r} 10 \frac{2}{3} \\ 10 \frac{2}{3} \\ 10 \frac{2}{3} \\ 10 \frac{2}{3} \\ 10 \frac{2}{3} \\ 10 \frac{2}{3} \\ \hline 60 \\ 4 \\ \hline 6 \boxed{64} \boxed{10 \frac{2}{3}} \\ 60 \end{array}$$

105

110

115

120

In order to set the first stake at the right point of tangent it is necessary to make an extra measurement of thirty-one feet from the beginning of the easement out upon the straight portion of the track or rail. This is in order to make the measurement in the center of the cord and set a stake directly opposite the point of tangent in the center of the track.

Every curve of a different degree has its own scale, to produce the required easement between the body of the curve and where the straight portion of the track merges thereinto, as the various curves of a track vary. The rule 41 is provided so that the degree of curve in inches subtracted from a half gauge of a track in inches is 28 1/4 130

and divided into six equal parts, so that equal string lengths of thirty-one feet may be in the form of a rule, the notches 41^a of which adjacent the graduations numbered 5 1, 2, 3, 4, 5, 6 and 7 are provided for the purpose of measuring the easements of the curve. In order to accomplish this result the rule 41 is divided into six equal parts to apply to a four degree curve and the easements of other curves will be figured according to their respective degree of curve and so on. In other words there may be a plurality of rules 41, for measuring easements of various curves having different degree of curve, 10 and where the easements vary in their formation.

In measuring the curve and the easements thereof by this implement, four inches which is the degree of the easement is subtracted 20 from 28 $\frac{1}{4}$ leaving 24 $\frac{1}{4}$. The rule 41 is divided into six equal parts, and the block 38 of the slide, which also carries the rule 41 is placed so that its indicator is opposite the graduation 24 $\frac{1}{4}$ from the center of the aperture of 25 the enlargement of the gauge rule. After setting the block 38 at this point it is necessary to attach and move the slide of the facing plate of the block 39 adjacent the ball of the rail.

56 $\frac{1}{2}$ is the standard gauge between the rails of a track, therefore 28 $\frac{1}{4}$ is half the distance, and the reason 4" is subtracted from 28 $\frac{1}{4}$ leaving 24 $\frac{1}{4}$, is that the 4" stands for the easement. In other words the easement is 30 the distance between a 62 foot curve track cord and the rail at every thirty-one feet, for six string lengths of thirty-one feet as above explained, on a basis of a four degree curve. The distance between said cord 40 and the rail at these points to provide an easement is

$$\frac{10 \frac{2}{3}}{16}$$

45 of an inch, there being six of them, makes 64/16, changed to inches equals 4".

If the track has a six degree curve, 6" is subtracted from 28 $\frac{1}{4}$. If you have a ten degree curve, 10" is subtracted from 28 $\frac{1}{4}$, and 50 so on, according to the degree or curve.

Another example is that should the track have a ten degree curve, 10" is subtracted from 28 $\frac{1}{4}$ leaving 18 $\frac{1}{4}$, in which case the block 38 which carries the rule 33 is set at 55 18 $\frac{1}{4}$. On a curve of this character 248' is used for the easement from point of tangent to point of full curve, dividing 248' by 31 feet will give 8 measurements for the curve, in order to find out what rate the easement 60 will extend. This easement of 10" every thirty-one feet multiplied by 16 equals 160/16, divided by 8 equals 20/16 or an inch and a quarter every thirty-one feet from the curve track cord to the rails, for 8 measure-

ments, which is the length of the easement 65 on a ten degree curve, hence the degree of curve is subtracted from 28 $\frac{1}{4}$, and divided into as many parts as there are lengths in the easements, for instance such as 20/16 of an inch on the curve. Therefore the subtraction is made only for the purpose of 70 running the easement on the curve. It is to be noted that it does not change the length of the rule 33 when attaching the easement rule, because when placing the indicating 75 block 38 at 18 $\frac{1}{4}$ and then attach an easement rule of 10", the block 39 is still at 28 $\frac{1}{4}$ from the center of the centering pin of the central block 23 to notch No. 1 on easement rule 41.

The invention having been set forth, what 80 is claimed is:

1. In a track gauge, a gauge body, having means at one end for attachment to one rail, and means detachably connected to the other end and offset laterally from the gauge body 85 for measuring and ascertaining the spacing between the rails.

2. In a track gauge, a gauge body, having means at one end for attachment to one rail, and means detachably connected to the other 90 end for measuring and ascertaining the spacing between the rails, a centering pin adjustable on the gauge body and having a pointer to engage a stake between the rails.

3. In a track gauge, a gauge body, having means at one end for attachment to one rail, and means detachably connected to the other end and offset laterally from the gauge body for measuring and ascertaining the spacing 95 between the rails, said detachable means at one end of the body of the gauge having a depending lug to contact with the rail and provided with a transverse slot, and a rule for measuring the elevation of the outer rail 100 adjustably mounted in said slot.

4. In a track gauge, a gauge body, having means at one end for attachment to one rail, and means detachably connected to the other end and offset laterally from the gauge body 110 for measuring and ascertaining the spacing between the rails, and a spirit level carried by the gauge body.

5. In a track gauge, a gauge body, having means at one end for attachment to one rail, and means detachably connected to the other end for measuring and ascertaining the spacing between the rails, a guide mounted on the side of the gauge body, a fulcrum head adjustable on the gauge body and engaged with said guide, to hold the fulcrum head horizontally on the gauge body, and a pointer to engage through the fulcrum head and adapted to engage a stake between the rails.

6. In combination with a track gauge including a gauge body and a fulcrum head, of a gauge rule adjustably connected to the fulcrum head and provided with a slide, said

slide comprising a pair of blocks, adjustable along the gauge rule, one of said gauge blocks having a facing plate adapted to engage the inner edge of the ball of the rail, and a rule detachably connected to the blocks of said slide and provided with graduations and notches, adapted to cooperate with a standard curve track cord, for measuring and ascertaining the degree of easement of the curve.

7. In a device for the purpose indicated, a gauge rule adapted to be carried by a track gauge, said rule having a centering point at one end adapted to engage a tack and a stake between the rails of a curve, a slide on said gauge rule and including an easement measuring rule having graduations and notches, adapted for cooperation with a standard curve track cord, for measuring and ascertaining the degree of the easement of the curve of a track.

8. In a device for the purpose indicated, a gauge rule adapted to be carried by a track gauge, a fulcrum point adjacent one end of the rule and provided with means overlying the opposite edges of the rule for preventing the point from swiveling relatively to the rule, means engaging through the point and the rule for clamping the same thereto, a slide adjustable on the other end of the rule and having a facing plate at one end to engage the inner edge of a ball of the outside rail, and a rule carried by said slide and provided with graduations and notches for cooperation with a standard curve track cord, for measuring and ascertaining the degree of easement of the outer rail of a track curve.

9. A gauge rule for mounting on a track gauge, means at one end of the rule for supporting the rule upon a stake between two rails, an easement measuring rule mounted for adjustment on the gauge rule and provided with means adapted for cooperation with a standard curve track cord, for measuring and ascertaining the easement of the outer curved rail.

10. The combination with a track gauge provided with means at one end for operative connection to one rail of a curved track, a gauge rule, means on the track gauge for supporting the gauge rule in an offset position and in parallelism with the track gauge, means operatively mounted on the track gauge and connecting with one end of the gauge rule for indicating the location of a centering stake between two rails, means on the gauge rule for cooperation with a standard curve track cord, for measuring and

ascertaining the easement of the outer rail of a track.

11. The combination with a track gauge provided with means at one end for operative connection to one rail of a curved track, a gauge rule, means on the track gauge for supporting the gauge rule in an offset position and in parallelism with the track gauge, means operatively mounted on the track gauge and connecting with one end of the gauge rule for indicating the location of a centering stake between two rails, means on the gauge rule for cooperation with a standard curve track cord, for measuring and ascertaining the easement of the outer rail of a track, and means for holding the easement measuring means in different positions on the gauge rule.

12. The combination with a track gauge provided with means at one end for attachment to one of the rails, a socket, a gauge extension operatively mounted in said socket, means for holding the gauge extension in different positions in the socket, said gauge extension having a vertical opening, and a rule mounted in said vertical opening and including a thumb screw whereby said rule may be held in different positions, for determining and measuring the height of the outside rail of a curved track.

13. The combination with a track gauge provided with means at one end for engagement with the ball of a rail, said means comprising a pair of forks provided with claws to engage one side of the ball of the rail, means having one end slidably and operatively connected to the shank of the pair of forks, and an extension at the other end to overlie the opposite side of the ball of the rail and provided with means for bearing against the ball of the rail to hold the track gauge in place, and means at the other end of the track gauge and including a ruler for measuring the height of an outside rail.

14. The combination with a track gauge provided with means at one end for attachment to the ball of a rail, a lateral support mounted on the gauge, a centering means on the track gauge and the support, a rule connected to the centering means end engaged with said supporting means, and an easement measuring and finding device mounted on said rule and adapted for cooperation with a standard curve track cord, for measuring and finding the degree of easement of a curve in a track.

In testimony whereof I hereunto affix my signature.

JUNIUS E. BUSBY.
